UNITED STATES PATENT OFFICE.

WILLIAM PERSON, OF ROCKFORD, ILLINOIS, ASSIGNOR TO ROCKFORD CABINET COMPANY,
OF ROCKFORD, ILLINOIS, A CORPORATION OF ILLINOIS.

CABINET.

No. 888,735.

Specification of Letters Patent.

Patented May 26, 1908.

Application filed March 9, 1908. Serial No. 419,915.

To all whom it may concern:

Be it known that I, WILLIAM PERSON, a citizen of the United States, residing at Rockford, in the county of Winnebago and State of Illinois, have invented certain new and useful Improvements in Cabinets, of which the following is a specification.

The object of this invention is to construct a cabinet in which a plurality of shelves are supported in guide-ways and capable of a sliding movement therein, and a connection of the shelves with a hinged door, so that the opening movement of the door will extend the shelves, and a closing movement thereof

will retract the shelves.

In the accompanying drawings, Figure 1 is a perspective view of my improved cabinet as seen from the rear face, the back of the cabinet being removed to better show the internal construction. Fig. 2 is a perspective view of the cabinet, in which the door is open and the shelves extended.

My improved cabinet comprises the sides 1 and 2, top 3, and bottom 4, secured together in any suitable manner. A door 5 has a hinge connection with the front edge of the side 1. The upper portion of the cabinet supports a drawer 6. To the inside of the sides 1 and 2 are secured guide-ways 7 and in any two oppositely disposed guide-ways is located a shelf 8, in a manner to slide freely therein.

To the under face of the horizontal partition 9 is connected a bar 10 by the hinges 11. This bar extends downward along the rear edges of the shelves 8. To the under face of each shelf are secured two cleats 12 which extend beyond the rear edge of the shelves, and from the projecting end of each cleat extends a pin 13, the pins of the cleats of a shelf extending toward one another, and overlapping the rear face of the bar as shown at Fig. 1.

The shelves are all of the same size, and are suitably spaced within the cabinet. To the inner face of the door 5 is secured a bracket 14, and to the lower end of the swinging bar 10 is connected an eye 15 by the nut 16. A rod 17 serves to connect the bracket 14 and the eye 15. When the door 5 is closed, the bar 10 will assume a substantially vertical position, and the shelves 8 will be withdrawn

within the case as shown at Fig. 1. In opening the door 5, the lower end of the swinging bar 10 will be moved toward the front of the cabinet which will extend the shelves varying distances as shown at Fig. 2. In closing the door, the swinging bar 10 will engage the pins 13 extending from the cleats 12 connected to the under face of the shelves, thereby withdrawing the shelves. By locating the shelves in guide-ways, the shelves will always remain the same distance apart throughout their movements. The shelves thus supported are free from oscillation and a steady movement will be imparted thereto.

As shown at Fig. 2, when the shelves are extended, each one will be extended farther than the one next above it, so that ready access may be had to the articles supported by them.

It is evident that in place of the guide-ways secured to the inner faces of the ends, the ends may be grooved to form supports for the shelves and still be within the scope of my invention.

I claim as my invention.

1. In a cabinet, in combination a casing provided with a door, a plurality of shelves supported to slide in suitable guideways, a bar hinged at its upper end to the casing, connections between the bar and shelves, and connections between the door and bar whereby the movements of the door will move the shelves.

2. In a cabinet, in combination a casing provided with a door, a plurality of shelves supported to slide in suitable guide-ways, a bar hinged at its upper end to the casing, cleats secured to the under face of the shelves, pins supported by the cleats, the bar located between the pins and rear edges of the shelves, and connections between the door and bar whereby the movements of the door will move the shelves.

In testimony whereof I have hereunto set my hand in presence of two subscribing witnesses.

WILLIAM PERSON.
